UNITED STATES PATENT OFFICE.

AUGUSTUS M. WING, OF PORTLAND, OREGON.

TYPE-WRITER CARRIAGE-RETURN.

1,152,684.

Specification of Letters Patent.

Patented Sept. 7, 1915.

Application filed September 2, 1914. Serial No. 859,902.

To all whom it may concern:

Be it known that I, AUGUSTUS M. WING, a citizen of the United States, residing at Portland, in the county of Multnomah and 5 State of Oregon, have invented certain new and useful Improvements in Type-Writer Carriage-Returns, of which the following is a specification.

This invention has reference to typewriting machines, and more particularly to means for returning the traveling member of the machine to its initial position after the completion of each line of printing.

Two classes of typewriters are ordinarily used, one having a cylindrical platen traveling longitudinally relative to the printing point, the other having a stationary platen on which the printing mechanism is mounted to travel. The device forming the subject matter of this invention adapts itself readily for use on both types of machines, and in order to simplify the description, reference is made to the first named structure only.

25 The object of my invention is to provide means for operating and returning the carriage without removing the operator's hands from the keyboard, and thus save the time necessary with the present devices to operate the carriage by hand and return the hand to the keyboard upon the completion of each printed line.

With this object in view, my invention consists in certain combinations of elements 35 to be hereinafter fully explained.

In order to fully comprehend my invention and the art to which it relates, reference is made to the following specification, taken in connection with the accompanying 40 drawings, which form part of this application, of which:—

Figure 1 is a front elevation of my invention connected to a typewriter and desk; Figs. 2 and 3 are details of a modified form 45 of bracket to be used in connection with a machine having the spacing lever at the left of the platen; Fig. 4 is a perspective of the connecting means with the line space lever; Fig. 5 is a side elevation of my invention; Fig. 6 is a front elevation of same; Fig. 7 50 is a detail; Fig. 8 is a perspective of the rail structure and stop; Fig. 9 is a perspective of the traveling pedal; Fig. 10 is a longi-

tudinal section through the tube and head; while Fig. 11 is a cover for the head. 55

Like characters of reference indicate like parts in the several figures of the drawing.

The only part of the typewriter which is directly concerned is the line space lever, which in Fig. 1 is designated by the reference numeral 1. This lever is shown positioned on the right hand side of the typewriter. In certain other machines this line space lever is mounted on the left side, but as it in all cases operates in substantially 60 the same manner, no further mention of this well known mechanism is thought necessary.

The typewriter is placed on an ordinary desk 2 to which is rigidly secured a tubular column 3. Below the table, and in continued alinement with said column is a tube 4 containing a second tube 13, said tube 4 terminating in a chamber 5. A flexible member 6 is by means of a bifurcated hook 7, attached to clamp 8, which fastens to line 65 space lever 1. Said flexible member passes through the tubular column 3 and the tube 13 to a weight 9 in tube 13. The tubular column 3 terminates at the top in a hollow head 10, in which a grooved wheel 11 is 70 rotatably fixed on pin 12. The inner tube 13 inserted into tube 4 has attached thereto a threaded thimble 14^a at its upper end, (to engage the weight 9 and thus operate the carriage through flexible member 6) and 75 guides 14—15 of approximately the inside diameter of tube 4. A helical spring 16 encircles tube 13 below guide 14 and passes the full distance intermediate said guide and shoulder 17 of projection 18 on chamber 5. 80 A flexible member 19 passes from the lower end of tube 13 downwardly and contacts with sheave 20 which is revolvably mounted in chamber 5. A slot 22 is cut in said chamber to allow the chain to pass without said 85 chamber in order that the free end of said chain may be attached to hook 23 of traveling pedal 24 which moves horizontally on tracks 25; said tracks being constructed in this instance of longitudinal rods which are 90 fastened at one end by a spreader 26 and at the reverse end by a transverse rod 27 which is supported by lugs 29 which fit into slots 28 in casting 30.

Attached to frame 31 is an angle-plate 31^a 95 to the horizontal leg of which casting 30 is

securely and rigidly attached, while at the opposite end of said angle-plate a small vertical pin is secured adapted to engage a hole in strap 33 attached to spreader 26, which 5 thus rests upon the floor in front of the desk and immediately below and at the right of the operator, so that the foot pedal 24 is thus brought into convenient position for operation by the right foot.

10 When assembled as described, the typist operates the machine until the carriage goes to its extreme distance, and by means of the flexible member 6 carries weight 9 upwardly. The foot of the operator then moves pedal 15 24 longitudinally of tracks 25 in a direction away from the operator or rearwardly of the desk. This motion of pedal 24 by means of flexible member 19 draws tube 13 downwardly into tube 4, and when thimble 14^a is thus 20 brought into contact with the upper end of weight 9, the flexible member 6 attached to said weight is thus drawn downwardly through tubular column 3, and thus the carriage is moved toward the right, and returned to its initial position as regards the 25 typewriter.

It will be noted that pedal 24 is mounted on tracks 25 by wheels 32, and further that a stop-spring 34 is attached to angle-plate 30 35, said angle-plate being fastened to strip 33 and serves to limit the backward movement of pedal 24, which is brought to said position by the extension of spring 16, which was compressed during the operation 35 of returning the carriage.

To aid in assembling my invention a removable cover 37 is placed on chamber 5 and secured thereto by nut 38 which screws to the bearing pin 38^a of sheave 20, which pin 40 45 is rigidly secured to the vertical leg of angle-plate 31^a.

Chamber 5 with its attached tube 4 and the contents thereof is freely mounted upon pin 38^a, so that the removal of nut 38 enables 45 the entire structure consisting of chamber 5 and tube 4 with its contents to be removed for inspection or repairs. A small clip 39 is secured to frame 31, and its outwardly extending end 39^a bent into a portion 50 of a circle to partially surround tube 4 and thus hold the same vertically and in alignment with tubular column 3 when in use, and prevent the structure from rotating about pin 38^a.

55 My invention may be constructed of any material and made any size deemed suitable for all the requirements of such a device, and while I have illustrated and described a preferred form of construction and combinations of elements considered essential in 60 materializing the same, I wish to include in his application all mechanical equivalents and substitutes that may be fairly consid-

ered to come within the scope and purview of my invention as defined in the appended 65 claims.

Having thus fully described my invention so that others skilled in the art to which it relates may be enabled to construct and use the same, what I claim and desire to secure 70 by Letters Patent, is:—

1. In a device of the character described, a clamp secured to a line space lever, a bifurcated hook attached to said clamp, a tube attached to a typewriter desk, a fixed tube 75 attached below the desk, a vertically movable tube within said fixed tube, a flexible member attached to the bifurcated hook and passing downwardly to a weight in the vertically movable tube, a chamber secured to 80 the lower part of the fixed tube, a flexible member fixed at one end to said vertically movable tube, means attached to said flexible member at its free end without the chamber to operate the same, and a spring within the fixed tube to bring said operating means back to its normal position, for the 85 purposes set forth.

2. In a device of the character described, a pair of telescopic tubes, a flexible member 90 attached to a typewriter carriage and passing downward into the inner tube of said pair of telescopic tubes, a counterweight attached to said flexible member within said inner tube, a flexible member attached to the 95 inner tube and passing outside of the outer tube, and means to operate said flexible member, substantially as described.

3. In a device of the character described, a pair of telescopic tubes, a flexible member 100 attached to the lower end of the inner tube and passing outside of the outer tube to a foot pedal, a counterweight within said inner tube, a flexible member attached to said counterweight and passing outside of said 105 inner tube to a typewriter carriage substantially as described.

4. In a device of the character described, a pair of telescopic tubes, and means to connect the inner tube to a typewriter carriage 110 and means to connect the inner tube to a foot pedal, substantially as described.

5. In a device of the character described, a pair of telescopic tubes, counterweighted flexible means to connect the inner tube to a 115 typewriter carriage, and flexible means to connect said inner tube to a foot pedal, substantially as described.

In testimony whereof I claim the foregoing as my own, I hereunto affix my signature 120 in the presence of two witnesses.

AUGUSTUS M. WING.
